UNITED STATES PATENT OFFICE.

FREDERICK WINK, OF PHILADELPHIA, PENNSYLVANIA, ASSIGNOR TO
THOMAS DOLAN, OF SAME PLACE.

DESIGN FOR SHAWL-PATTERN.

Specification forming part of Design No. 6,085, dated August 20, 1872.

Specification describing a Design for a
Shawl-Pattern, invented by FREDERICK
WINK, of Philadelphia, Pennsylvania.

Design for a Shawl-Pattern.

The design is clearly shown in the accompanying drawing, and is composed of wide and narrow stripes A and B, and of intervening narrow bars D, the latter being separated transversely throughout their entire length into equal sections, each of which is ornamented by diagonal lines and diamonds, as shown. The stripes A and B are composed of a series of parallel minor stripes or ribs of varying width, and the former has two ornamented ribs, a a,

and the latter a central rib, b, of the same character as the bars D.

Irrespective of the colors employed, I claim—

The design for a shawl-pattern, substantially as described, and as represented in and by the accompanying drawing.

In testimony whereof I have signed my name to this specification in the presence of two subscribing witnesses.

FRED. WINK.
